UNITED STATES PATENT OFFICE.

JOHN YEMIKER, OF AKRON, OHIO, ASSIGNOR OF FORTY-NINE ONE-HUNDREDTHS TO
ROBERT H. FOWLER, OF AKRON, OHIO.

COLLAPSIBLE CORE.

1,079,038.

Specification of Letters Patent. Patented Nov. 18, 1913.

Application filed August 17, 1912. Serial No. 715,651.

To all whom it may concern:

Be it known that I, JOHN YEMIKER, a citizen of the United States, residing at Akron, in the county of Summit and State of Ohio, 5 have invented certain new and useful Improvements in Collapsible Cores, of which the following is a specification, reference being had to the accompanying drawings.

This invention comprehends certain new 10 and useful improvements in collapsible cores or mandrels designed particularly for use in molding rubber tires, or analogous articles.

The invention has for its primary object 15 a core, the parts of which are so constructed and arranged that the necessity of employing contracting rings, mandrels, or bolts for drawing the sections of the core together and holding them in assembled relation, is entirely done away with, whereby 20 the core will possess to a considerable degree, the characteristics of simplicity, durability and efficiency in operation, as well as reducing to a minimum, the time required for assembling and disassembling the sections 25 of the core. And the invention also aims to generally improve devices of this class and to render them more useful and commercially desirable.

With these and other objects in view, as 30 will more fully appear as the description proceeds, the invention consists in certain constructions, arrangements and combinations of the parts that I shall hereinafter fully describe and claim.

For a full understanding of the invention, 35 reference is to be had to the following description and accompanying drawing, in which—

Figure 1 is an elevation of my improved 40 collapsible core; Fig. 2 is a transverse sectional view thereof on the line 2—2 of Fig. 1; and Fig. 3 is a detailed perspective view of one of the connecting members herein-after specifically described.

Corresponding and like parts are referred 45 to in the following description and designated in the accompanying drawing by like reference characters.

My improved collapsible core is composed 50 of a plurality of separable sections which are segmental in form and tubular. In the present instance, four of these sections are employed, the same being designated 1, 2, 3 and 4, although it is to be understood that 55 the invention is not limited in this regard.

In the present embodiment of the invention, the adjoining ends of the sections 2, 3 and 4 are substantially radially disposed, but the adjoining ends of the sections 2, 4 and 1 are disposed in planes oblique to the radii of the annular body of the core, the inner portion 60 of the section 1 being of greater length than the outer or peripheral portion, whereby the member 1 will serve in the nature of a key and may be readily moved inward out 65 of engagement with the obliquely arranged ends of the adjacent members 2 and 4 when it is desired to collapse the core, preparatory to removing it from the molded tire casing. Manifestly, the abutting ends of the sections 70 2, 3, and 4 may be radially or otherwise disposed, because these sections may be removed from the tire casing after the key member 1 has been removed.

Each of the sections which together form 75 the body of the core is formed on its inner side with a widened or thickened segmental flange, the ends of said flanges, when the sections are assembled, abutting against each other to constitute an annular thickened 80 bead which is adapted to be engaged by connecting wedge members 5. The number of the connecting members 5 is equal to the number of segmental core members employed, each of said connecting members being formed with an elongated body portion which terminates at each end in a head 6 which, in the present instance, has its side edges plane, and oblique to each other, joined together at their outer ends by a transversely 85 straight or plane end surface. The adjoining ends of the segmental members 1, 2 and 3 are formed with communicating recesses 7 which correspond in shape, when the parts are assembled, to the connecting members 5 and which, like the connecting members, are transversely tapered from one side face of the bead to the other, whereby when the connecting members 5 are driven laterally into the recesses, they will tend to draw the 90 segmental members together and hold them tightly in assembled relation.

In order to prevent sidewise movement, the segmental members which form the body of the core, are formed at their ends and at their peripheral edges with registering recesses 8 designed to receive keys 9, in an evident manner.

From the foregoing description in connection with the accompanying drawing, the 110

operation of my improved collapsible core will be apparent. In the practical use of the device, when setting up the core, the parts are assembled with their ends abutting, and the connecting members 5 are driven into the recesses 7, thereby producing a wedging action and a drawing or tensioning effect on the segmental members 1, 2, 3 and 4 and tending to bind them closely together in assembled relation. The keys 9 are slipped into place and prevent any sidewise movement or displacement, as above specified.

It will thus be seen that I have provided a very simple, durable and efficient construction of collapsible core, wherein the parts are so arranged and formed that the operation of assembling and disassembling the parts may be very quickly and easily effected and without the use of contracting rings or bolts.

While the accompanying drawing illustrates what I believe to be the preferred embodiment of my invention, it is to be understood that the invention is not limited thereto, but that various changes may be made in the construction, arrangement and proportions of the parts without departing from the scope of the invention, as defined in the appended claims.

30. What I claim is:—

1. A collapsible core for manufacturing pneumatic tires, comprising a plurality of separable segmental sections adapted to abut against each other to produce a circular body and provided at their inner edges with enlarged flanges of rectangular form in cross section connected with the main portion of the sections by reduced neck portions, said flanges forming an annular bead 35 when the sections are secured together, the adjoining ends of said flanges being formed with corresponding and communicating recesses provided with enlarged ends, said recesses being transversely tapered, and I-shaped connecting members embodying elongated body portions and enlarged dove-tailed and beveled heads, said connecting

members tapering transversely and being adapted to be driven into the recesses with the heads lying in the enlarged ends of the latter, thereby drawing the sections together. 50

2. A collapsible pneumatic tire core, comprising a plurality of separable segmental abutting sections each provided with a flange at its inner edge of rectangular form in cross section, said flange being connected with the main portion of the section by a neck portion, the adjoining ends of said flanges being formed with corresponding and communicating recesses having enlarged inner ends, said recesses being transversely tapered, I-shaped connecting members adapted to be driven into the recesses with the heads thereof lying in the enlarged inner ends of said recesses to draw the sections together, said connecting members being tapered to correspond with the recesses, and means to prevent lateral movement of the outer ends of the sections. 60

3. A collapsible core for pneumatic tires, comprising a plurality of separable abutting sections producing a circular body, each section being provided at its inner edge with an enlarged flange connected with the main portion thereof by a neck portion, the adjoining ends of said flanges being provided with corresponding and communicating recesses provided with dove-tail-shaped inner ends, said recesses being transversely tapered, I-shaped connecting members adapted to be driven into the recesses with the heads thereof lying in the enlarged inner ends of said recesses to draw the sections together, said connecting members being tapered to correspond with the recesses, and means engaged in the outer ends of the sections to prevent lateral movement of the latter. 70

In testimony whereof I hereunto affix my signature in the presence of two witnesses.

JOHN YEMIKER.
